FAN BLADE UNIT

Ottis D. Twist, 402 Pittsfield Road, Mount Sterling, Ill.

Filed May 4, 1962, Ser. No. 69,973

Term of patent 14 years

(Cl. D62—4)

FIG. 1 is a front view of a fan blade unit embodying my new design; FIG. 2 is a back view thereof; and FIG. 3 is an edge view in the direction of arrows 3—3 of FIG. 2.

I claim:

The ornamental design for a fan blade unit, substantially as shown.
